AUTOMOBILE LOCK

Alexander C. Mabee, Villa Park, Ill., assignor to
 Oakes Products Corporation, North Chicago,
 Ill., a corporation of Michigan

Application May 18, 1936, Serial No. 80,385

11 Claims. (Cl. 70—252)

My invention relates to automobile locks and particularly to a unitary lock structure operable for locking the steering and the ignition against unauthorized operation, the general object being to produce a simple and efficient lock structure which may be economically manufactured.

An important object of the invention is to provide a lock structure in which the lock member is in the form of a swinging bolt normally operable in one plane into steering locking or unlocking position and adapted, when moved to unlocking position, to be shifted into another plane into operative engagement with a switch so that movement of the bolt in said second plane may be used for turning the ignition switch on or off.

A further object of the invention is to control the swinging of the locking bolt by means of a lock structure preferably of the cylinder-tumbler type, with the locking bolt secured to the tumbler cylinder and with spring means effective to shift the bolt and lock structure outwardly as soon as the bolt has been moved to unlocking position, for passage into its second plane of operation, whereby swing of the bolt by turning of the key will then effect operation of the switch.

The above referred to and other features of the invention are shown incorporated in the structure disclosed on the drawing, in which:

Figure 1 is a vertical section of the lock structure on plane I—I of Figure 2, and shows the lock applied to a steering column;

Figure 2 is a section on plane II—II of Figure 1;

Figure 3 is a section on plane III—III of Figure 1;

Figure 4 is a section on plane IV—IV of Figure 3;

Figure 5 shows the movable switch member within its housing;

Figure 6 is a section like Figure 1 but showing a modified arrangement; and

Figure 7 is a view of the end of the shaft extending from the tumbler barrel showing the modified mounting thereon of the locking member.

The lock structure comprises the body 10 having the semi-circular arms 11 and 12 extending therefrom for surrounding the tube 13 through which the steering shaft 14 extends, the ends of the arms being drawn together by a screw 15 so that the arms will securely clamp the tube 13 to hold the lock structure in position there-

on. A locking ring or bushing 16 is inserted between the steering shaft and the tube 13 and is rigidly secured to the shaft and has the substantially V-shape locking notch 17 therein which registers with the opening 18 in the tube 13.

Within the lock body 10 are the outer and inner operating chambers 19 and 20 separated by a partition wall 21 which may be removable. As shown, the body 10 has the slot 22 around the chambers into which the partition wall may be slid when the lock structure is assembled. Such insertion of the wall may be through the bottom of the lock body which is normally open but which after assembly is closed by a cover plate 23.

The lock body 10 has the upper annular extension 24 for receiving the cylindrical frame 25 of a tumbler lock structure, said lock frame receiving the tumbler cylinder 26 into which a key may be inserted for turning thereof in a manner well understood in the art.

On the lock body, opposite the extension 24, is the extension 27 having the cylindrical bore 28 for receiving the cylindrical extension or plunger 29 on the lock tumbler cylinder, the axis of the lock structure being at right angles to the axis of the steering shaft 14. Secured to the plunger 29 adjacent to the end of the lock cylinder, as by means of a set screw 30, is the locking member 31 in the form of a rectangular bolt adapted to be swung normally in the operating chamber 20 when the lock cylinder is turned. The chamber 20 is in alignment with the opening 18 in the tube 13 and the locking notch 17 in the bushing 16 on the steering shaft. A spring 32 in the bore 28 of the extension 27 tends to shift the lock structure and locking bolt outwardly, but when the bolt is in locking position with its outer end in the locking notch 17, shifting of the lock structure is prevented by the engagement of the lock bolt against the side of the locking notch and against the partition 21. When the bolt is in locking position and the key is withdrawn from the lock, the bolt will be held in locking position as the tumblers will then lock the lock cylinder to the lock frame 25.

The partition wall 21 has a vertical passageway 33 therethrough, and when the key is inserted in the lock and turned to swing the locking bolt 31 to unlocking position, the bolt will be in alignment with the passageway 33 and will then be free so that the force of the spring 32 will shift the bolt through the passageway and into the operating chamber 19, and the lock cylinder and its frame 25 will be shifted outwardly in the extension 24. The lock frame 25 is held

against rotary movement by means of a pin 34 in the extension wall engaging in the longitudinally extending slot 35 in the frame, the slot being of sufficient length to permit the axial shift 5 of the lock structure when the bolt is swung to unlocking position. When the key is turned in the lock for swing of the locking bolt to unlocking position, the swing of the bolt will be stopped by its engagement with the abutment face 36 10 on the wall of the housing 10, and the bolt will then be accurately aligned for shift through the passageway 33 and into the operating chamber 19. The bolt has a tail pin 37 extending therefrom for cooperation with the switch means to 15 be described later, and the partition wall 21 has the passageway 38 for this tail piece when the bolt is shifted into the operating chamber 19.

The switch structure comprises a housing 39 which may be secured to the cover plate 23, and 20 in this housing is a movable switch member 40 in the form of a rectangular block of insulating material and carrying a switch blade 41. The switch block is pivoted at one end as by means of a pin 42 and with the corresponding end of 25 the switch blade in electrical engagement with a terminal post 43 on the outside of the housing, the housing also supporting another terminal post 44 adapted for engagement with the free end of the switch blade when the switch block 30 is turned.

At its outer end the switch block has an up-standing extension 45 provided with slot 46. As shown in Figures 2 and 3, when the switch is in 35 open position, the slot 46 will be in alignment with the passageway 38 in the partition 21 to receive the end of the tail pin 37 on the locking bolt 31 when the locking bolt and pin are shifted from the chamber 20 into the chamber 19. When the locking bolt passes into the chamber 19, 40 it will be freed from the abutment face 36 and it may then be turned with the lock cylinder so that its tail pin 37 will swing the switch block 40 for engagement of the switch blade 41 with the terminal 44 to close a circuit, and this 45 circuit may be the ignition circuit for the engine connected with the terminals 43 and 44.

When the bolt structure is within the operating chamber 19, the lock may be turned by the key for swing of the bolt and actuation of the 50 switch by the tail pin 37 to either closed or open position for closure or opening of the ignition circuit, and the spring 32 will tend to keep the bolt and lock structure in such switch operating field. During movement of the switch to circuit 55 closing position the locking bolt will be blocked by the partition wall 21, and the bolt and lock structure cannot then be shifted inwardly. Before the bolt can be shifted back into the operating chamber 20 for locking of the steering, 60 the bolt must first be swung back into registration with the passageway 33 after the ignition circuit has been opened and the pressure on the lock structure will shift it inwardly against the force of the spring 32 and the locking bolt will 65 be returned to operating chamber 20 whereafter turning of the key will swing the locking bolt back into steering locking position. In the operation of my improved lock structure it is therefore necessary to fully unlock the steering 70 before the switch can be operated to close the ignition circuit, and the ignition circuit must first be fully opened before the steering can again be locked, and accidental locking of the steering while the ignition circuit is on will be prevented.

75 In the structure of Figures 1, 2, and 3, the lock-

ing bolt 31 cannot be swung into the locking notch 17 unless the steering wheel is already in position or is brought into position for reception of the bolt end by the notch. To avoid such adjustment of the steering wheel the arrangement 5 shown in Figures 6 and 7 may be used. The locking bolt or bar 47 is rotatably mounted on the plunger end 29 of the lock cylinder and has the slot 48 for receiving a collar 49 secured on the plunger end as by a pin 50. This collar has the 10 tail pin 51 for cooperating with the switch, and the collar has a flat section 52 against which the bottom of the slot 48 in the lock bar is normally held by a spring 53 mounted on the pin 51. Figure 6 shows the locking bar in locking position with the base of the slot against the flat of the collar 49, and when the key is now turned in the lock, the engagement of the flat of the collar 49 with the bolt will swing the bolt out of locking position and into alignment with the passageway 33' through the partition 21', so that the lock bar structure may be shifted into the chamber 19 for operation to control the switch. When the lock bar structure is shifted back into the chamber 20 and turned towards steering locking 15 position, the end of the locking bar will engage in the locking notch 17 if such notch is in the proper position. If the notch is displaced from such locking position, the end of the bolt 20 will encounter the cylindrical face of the bushing 16, but the lock cylinder may be turned by the key back to normal position against the resistance of the spring 53. Then as soon as the steering wheel is turned to bring the locking notch 17 into alignment with the locking bolt, 25 the spring will swing the bolt into the notch, and the steering will be locked. The passage 33' through the partition 21 will be made of sufficient size to permit the locking bar and the tail pin 51 and the spring 53 to pass therethrough 30 into the operating chamber 19 after the locking bar has been swung to unlocking position.

I have thus shown a practical and efficient embodiment of the various features of my invention, but I do not desire to be limited to the exact construction, arrangement, and operation 45 shown and described, as changes and modifications may be made without departing from the scope of the invention.

I claim as follows:

1. A lock of the class described comprising a 50 locking bolt rotatable in either of two parallel planes, a single means for rotating said bolt in either plane, said bolt when rotated by said means in one plane being moved to locking or unlocking position, means for shifting said bolt into the other plane after it has been moved to unlocking position, and control means operated during rotation of said bolt by said operating means in said other plane.

2. A steering post-ignition lock comprising a 55 locking bar selectively shiftable to either one of two operating planes, a single actuating means for rotating said bar in either plane, said bar when rotated by said actuating means in one of said planes causing locking or unlocking of the steering, means for shifting said bar into the other operation plane after it has been moved from locking position in the first plane, a switch, and means whereby said switch is controlled during movement of said bolt in the second plane.

3. In a combined steering post and ignition lock, an actuating structure bodily movable into either one of two operating fields, a locking bar, and a control for an ignition circuit, said actuat-

ing structure when moved into one of said fields being operable to cause swing of said locking bar to lock or unlock the steering post, and when moved into the other field being operable to actuate said circuit control to open or close the circuit without locking of said steering post by said bar.

4. In a combination steering post and ignition lock, an actuating structure and means for bodily moving said structure into either of two operating fields, a lock bar carried by said structure, and a control for an ignition circuit, said actuating structure when in one of said fields being operable to cause swing of said bar to steering locking or unlocking position without affecting said circuit control, said structure when moved into the other field being operable to actuate said control for opening or closing of the ignition circuit without locking of the steering post by said bar.

5. In a combination steering and ignition lock, a rotatable actuating structure having a steering locking bar connected therewith and being axially shiftable to move said bar out of an effective operating field, said bar when in said field being rotatable by said actuating structure to lock or unlock the steering and when moved out of said field being ineffective to lock the steering, and an ignition circuit control operable by said actuating structure only when said bar is out of its effective field of operation.

6. In a combination steering and ignition lock, a rotatable actuating structure and a steering locking bar carried thereby, said bar being normally positioned by said actuating structure for rotation thereby to unlock the steering, means effective after unlocking of the steering to shift said structure to position said bar for rotation thereof by said structure without effecting re-locking of the steering, and a control for an ignition circuit operable by said actuating structure after shift thereof.

7. In a combination steering and ignition lock, a rotatable locking bar, an actuating structure normally positioning said bar in a plane in which it may be rotated to lock or unlock the steering, means effective after rotation of said bar to un-

locking position to shift the bar axially into a plane where rotation thereof cannot re-lock the steering, and an ignition circuit control operable by said actuating structure to open and close the ignition circuit after shift of said bar.

5

8. In a combination steering and ignition lock, a rotatable actuating structure having a locking bar extending laterally therefrom, said structure being normally in position for rotation thereof to swing said bar into steering locking or unlocking position, means effective after swing of said bar to unlocking position to shift said structure where rotation thereof cannot swing said bar for re-locking the steering, and control means operable after shifting of said structure to open 15 and close an ignition circuit.

10

9. In a combination steering and ignition lock, a rotatable actuating structure and a locking bar extending therefrom at right angles to its axis of rotation, said bar being normally in position 20 for swing thereof by said actuating member to lock or unlock the steering, means effective after swing of said bar to unlocked position to shift said bar to a position where swing thereof by said actuating structure will be ineffective to 25 re-lock the steering, and a control operable by said actuating structure after shift of said bar for opening and closing an ignition circuit.

20

10. In a combination steering and ignition lock, a rotatable locking bar shiftable from an effective 30 to an ineffective position of operation, actuating means for rotating said bar in its effective position to lock or unlock the steering, means effective after rotation of said bar to unlocking position to shift said bar to its ineffective position, 35 and a control operable by said actuating means after shift of said bar to open and close an ignition circuit.

30

11. In a steering lock, a casing, a locking bolt in said casing operable in either of two fields of 40 operation but being effective in only one of said fields to lock or unlock the steering, means for shifting the bolt to its ineffective field of operation after unlocking movement thereof in the effective field, and means for preventing removal 45 of said bolt from said casing during such shifting.

ALEXANDER C. MABEE.
